Primary Examiner — Elvin G Enad*Assistant Examiner* — Kazi Hossain(74) *Attorney, Agent, or Firm* — Studebaker & Brackett PC(57) **ABSTRACT**

In an electronic component, a multilayer body is formed by a plurality of stacked insulator layers. A coil includes at least one coil conductor layer provided on at least one of the insulator layers. External electrodes are embedded in a lateral surface of the multilayer body which is formed by a series of continuous perimeter edges of the plurality of insulator layers, and includes a plurality of stacked external conductor layers provided on the plurality of insulator layers. The external electrodes have different shapes. The external conductor layers and the first coil conductor, which are provided on the same insulator layer, are simultaneously formed by photolithography or printing.

ELECTRONIC COMPONENT

CROSS REFERENCE TO RELATED APPLICATIONS

This application claims benefit of priority to Japanese Patent Application No. 2012-001405 filed on Jan. 6, 2012, and to International Patent Application No. PCT/JP2012/078369 filed on Nov. 1, 2012, the entire content of each of which is incorporated herein by reference.

TECHNICAL FIELD

Field of the Disclosure

The present disclosure relates to an electronic component and more specifically relates to an electronic component which includes a coil.

BACKGROUND

An example of known conventional disclosures relating to electronic components is an inductor described in WO 2007/080680. The inductor is formed by providing a coil in a multilayer body which is formed by stacking insulator layers. An external electrode is embedded in a lateral surface of the multilayer body and is formed by photolithography simultaneously with formation of the coil. In the inductor described in WO 2007/080680, the external electrode and the coil are formed in the same step. Therefore, the positional relationship between the external electrode and the coil is unlikely to deviate from a predetermined positional relationship.

In a field to which the inductor described in WO 2007/080680 relates, a structure which can be configured to have arbitrary electric characteristics has been demanded.

SUMMARY

Problems to be Solved by the Disclosure

In view of the above, an object of the present disclosure is to provide an electronic component in which the positional relationship between the external electrode and the coil is unlikely to deviate from a predetermined positional relationship while the electronic component has a structure which can be configured to have arbitrary electric characteristics.

Solution to Problems

An electronic component according to the present disclosure includes: a multilayer body having a shape of a rectangular parallelepiped, and including a plurality of stacked insulator layers; a first coil including at least one first coil conductor layer provided on at least one of the plurality of the insulator layers; and first and second external electrodes embedded in a lateral surface of the multilayer body which is formed by a series of continuous perimeter edges of the plurality of insulator layers, the first and second external electrodes including a plurality of stacked external conductor layers, the plurality of stacked external conductor layers being provided to the plurality of insulator layers, wherein the first external electrode and the second external electrode have different shapes, and the external conductor layers and

2

the first coil conductor, which are provided to the same insulator layer, are simultaneously formed by photolithography or printing.

5 BRIEF DESCRIPTION OF THE DRAWINGS

FIG. 1 is a perspective view of the exterior of an electronic component according to one embodiment.

10 FIG. 2 is an exploded perspective view of the electronic component of FIG. 1.

FIGS. 3A to 3D are first to fourth plan views of manufacture of the electronic component, respectively.

15 FIGS. 4A to 4D are fifth to eighth plan views in manufacture of the electronic component, respectively.

FIGS. 5A to 5D are ninth to twelfth plan views in manufacture of the electronic component, respectively.

20 FIGS. 6A to 6D are thirteenth to sixteenth plan views in manufacture of the electronic component, respectively.

FIG. 7 is an equivalent circuit diagram of the electronic component.

25 FIG. 8 is a graph showing the relationship between the frequency and the attenuation of the output signal relative to the input signal in the electronic component.

FIG. 9 is an exploded perspective view of an electronic component according to the first variation.

30 FIG. 10 is an exploded perspective view of an electronic component according to the second variation.

FIG. 11 is a perspective view of the exterior of an electronic component according to the third variation.

DETAILED DESCRIPTION

Hereinafter, an electronic component according to an embodiment of the present disclosure is described.

35 Configuration of Electronic Component

Hereinafter, the configuration of an electronic component according to one embodiment is described with reference to the drawings. FIG. 1 is a perspective view of the exterior of an electronic component 10 according to one embodiment.

40 FIG. 2 is an exploded perspective view of the electronic component 10 of FIG. 1. In the following description, the layer-stacking direction of the electronic component 10 is defined as the “y-axis direction”. When viewed in plan from the y-axis direction, a direction in which the long side of the electronic component 10 is extending is defined as the “x-axis direction”, and a direction in which the short side of the electronic component 10 is extending is defined as the “z-axis direction”.

45 As shown in FIG. 1 and FIG. 2, the electronic component 50 10 includes a multilayer body 12, external electrodes 14 (14a, 14b), and coils L1, L2 (not shown in FIG. 1).

The multilayer body 12 is formed by a plurality of insulator layers 16 (16a to 16g) which are stacked so as to be arranged in this order from the negative direction side to 55 the positive direction side of the y-axis direction as shown in FIG. 2. The multilayer body 12 has a shape of a rectangular parallelepiped. Thus, the multilayer body 12 has lateral surfaces S1 to S4, an upper surface S5, and a lower surface S6. The lateral surface S1 is a surface of the multilayer body 12 which is on the positive direction side of the z-axis direction. The lateral surface S2 is a surface of the multilayer body 12 which is on the negative direction side of the z-axis direction. When the electronic component 10 is mounted to a circuit board, the lateral surface S2 serves as a mounting surface which is to face the circuit board. The lateral surface S1 is formed by a series of continuous long sides (i.e., perimeter edges) of the insulator layers 16 which are on the 60 65

positive direction side of the z-axis direction. The lateral surface S2 is formed by a series of continuous long sides (i.e., perimeter edges) of the insulator layers 16 which are on the negative direction side of the z-axis direction. The lateral surface S3 is a surface of the multilayer body 12 which is on the negative direction side of the x-axis direction. The lateral surface S4 is a surface of the multilayer body 12 which is on the positive direction side of the x-axis direction. The lateral surface S5 is formed by a series of continuous short sides (i.e., perimeter edges) of the insulator layers 16 which are on the negative direction side of the x-axis direction. The lateral surface S6 is formed by a series of continuous short sides (i.e., perimeter edges) of the insulator layers 16 which are on the positive direction side of the x-axis direction. The lateral surfaces S3, S4 are adjacent to the lateral surface S2. The upper surface S5 is a surface of the multilayer body 12 which is on the positive direction side of the y-axis direction. The lower surface S6 is a surface of the multilayer body 12 which is on the negative direction side of the y-axis direction.

The insulator layers 16 have a rectangular shape as shown in FIG. 2 and are made of an insulating material whose main component is borosilicate glass, for example. In the following description, a surface of the insulator layers 16 which is on the positive direction side of the y-axis direction is referred to as "front surface", and a surface of the insulator layers 16 which is on the negative direction side of the y-axis direction is referred to as "rear surface".

The coil L1 is formed by coil conductor layers 18 (18a to 18e) and via hole conductors v1 to v4. The coil L1 has such a helical shape that it leads from the negative direction side to the positive direction side of the y-axis direction while circling around clockwise when viewed in plan from the positive direction side of the y-axis direction. The coil conductor layers 18a to 18e are provided on the front surfaces of the insulator layers 16g to 16k and have a shape of a rectangular annulus from which one side is cut away. The coil conductor layers 18a to 18d have $\frac{3}{4}$ turn, and the coil conductor layer 18e has $\frac{1}{2}$ turn. The coil conductor layers 18 are made of, for example, an electrically-conductive material whose main component is Ag. In the following description, an end of the coil conductor layer 18 which is on the upstream side when viewed in a clockwise direction is referred to as "upstream end", and the other end of the coil conductor layer 18 which is on the downstream side when viewed in a clockwise direction is referred to as "downstream end".

The via hole conductors v1 to v4 penetrate through the insulator layers 16h to 16k, respectively, in the y-axis direction. The via hole conductors v1 to v4 are made of, for example, an electrically-conductive material whose main component is Ag. The via hole conductor v1 connects the downstream end of the coil conductor layer 18a to the upstream end of the coil conductor layer 18b. The via hole conductor v2 connects the downstream end of the coil conductor layer 18b to the upstream end of the coil conductor layer 18c. The via hole conductor v3 connects the downstream end of the coil conductor layer 18c to the upstream end of the coil conductor layer 18d. The via hole conductor v4 connects the downstream end of the coil conductor layer 18d to the upstream end of the coil conductor layer 18e.

The coil L2 is formed by coil conductor layers 20 (20a to 20e) and via hole conductors v5 to v8. The coil L2 has such a helical shape that it leads from the negative direction side to the positive direction side of the y-axis direction while circling around anticlockwise when viewed in plan from the

positive direction side of the y-axis direction. The coil conductor layers 20a to 20e are provided on the front surfaces of the insulator layers 16g to 16k and have a shape of a rectangular annulus from which one side is cut away. The coil conductor layers 20a to 20d have $\frac{3}{4}$ turn, and the coil conductor layer 20e has $\frac{1}{2}$ turn. The coil conductor layers 20 are made of, for example, an electrically-conductive material whose main component is Ag. In the following description, an end of the coil conductor layer 20 which is on the upstream side when viewed in an anticlockwise direction is referred to as "upstream end", and the other end of the coil conductor layer 20 which is on the downstream side when viewed in an anticlockwise direction is referred to as "downstream end".

The via hole conductors v5 to v8 penetrate through the insulator layers 16h to 16k, respectively, in the y-axis direction. The via hole conductors v5 to v8 are made of, for example, an electrically-conductive material whose main component is Ag. The via hole conductor v5 connects the downstream end of the coil conductor layer 20a to the upstream end of the coil conductor layer 20b. The via hole conductor v6 connects the downstream end of the coil conductor layer 20b to the upstream end of the coil conductor layer 20c. The via hole conductor v7 connects the downstream end of the coil conductor layer 20c to the upstream end of the coil conductor layer 20d. The via hole conductor v8 connects the downstream end of the coil conductor layer 20d to the upstream end of the coil conductor layer 20e.

The downstream end of the coil conductor layer 18e and the downstream end of the coil conductor layer 20e are connected to each other. Thus, the coils L1, L2 are connected in series.

As shown in FIG. 1, the external electrode 14a is embedded in the lateral surfaces S2, S3 of the multilayer body 12 which are formed by a series of continuous perimeter edges of the insulator layers 16a to 16q. A portion of the external electrode 14a which is exposed to the outside of the multilayer body 12 extends over the lateral surfaces S2, S3. Thus, the external electrode 14a is L-shaped when viewed in plan from the y-axis direction. As shown in FIG. 2, the external electrode 14a is formed by stacked external conductor layers 25 (25a to 25i).

The external conductor layers 25 (25a to 25i) are stacked as shown in FIG. 2 so as to penetrate through the insulator layers 16e to 16m in the y-axis direction and are electrically coupled together. When viewed in plan from the y-axis direction, the external conductor layers 25a to 25i are L-shaped and are in contact with the short sides of the insulator layers 16e to 16m which are on the negative direction side of the x-axis direction and with the long sides of the insulator layers 16e to 16m which are on the negative direction side of the z-axis direction. The external conductor layer 25c is connected to the upstream end of the coil conductor layer 18a.

As shown in FIG. 1, the external electrode 14b is embedded in the lateral surfaces S2, S4 of the multilayer body 12 which are formed by a series of continuous perimeter edges of the insulator layers 16a to 16q. A portion of the external electrode 14b which is exposed to the outside of the multilayer body 12 extends over the lateral surfaces S2, S4. Thus, the external electrode 14b is L-shaped when viewed in plan from the y-axis direction. As shown in FIG. 2, the external electrode 14b is formed by stacked external conductor layers 35 (35a to 35i).

The external conductor layers 35 (35a to 35i) are stacked as shown in FIG. 2 so as to penetrate through the insulator

layers **16e** to **16m** in the y-axis direction and are electrically coupled together. When viewed in plan from the y-axis direction, the external conductor layers **35a** to **35i** are L-shaped and are in contact with the short sides of the insulator layers **16e** to **16m** which are on the positive direction side of the x-axis direction and with the long sides of the insulator layers **16e** to **16m** which are on the negative direction side of the z-axis direction. The external conductor layer **35c** is connected to the downstream end of the coil conductor layer **20a**.

Portions of the external electrodes **14a**, **14b** which are exposed to the outside of the multilayer body **12** are plated with Sn and Ni for anticorrosion purposes.

On both sides of the external electrodes **14a**, **14b** in terms of the y-axis direction, the insulator layers **16a** to **16d** and **16n** to **16q** are stacked. As such, the external electrodes **14a**, **14b** are not exposed at the upper surface **S5** and the lower surface **S6**.

Here, the external electrode **14a** and the external electrode **14b** have different shapes each other. In the present embodiment, the thickness of the external electrode **14a** is different from the thickness of the external electrode **14b**. Specifically, the line width **W1** of the L-shaped external conductor layers **25** is greater than the line width **W2** of the L-shaped external conductor layers **35**. As such, the distance between the external electrode **14a** and the coil **L1** is smaller than the distance between the external electrode **14b** and the coil **L2**.

The external conductor layers **25c** to **25g** and **35c** to **35g**, which are provided on the same insulator layers **16g** to **16k** on which the coil conductor layers **18a** to **18e** and **20a** to **20e** are provided, are formed by photolithography or printing simultaneously with formation of the coil conductor layers **18a** to **18e** and **20a** to **20e**. The simultaneous formation herein means that, in the case of photolithography, the coil conductor layers **18a** to **18e** and **20a** to **20e** and the external conductor layers **25c** to **25g** and **35c** to **35g** are exposed and developed using the same photomasks. In the case of printing, it means that the coil conductor layers **18a** to **18e** and **20a** to **20e** and the external conductor layers **25c** to **25g** and **35c** to **35g** are formed using the same screen plates.

Method for Manufacturing Electronic Component

Hereinafter, a method for manufacturing the electronic component **10** according to the present embodiment is described with reference to the drawings. FIG. 3 through FIG. 6 are plan views of the electronic component **10** during manufacture.

Firstly, an insulating paste whose main component is borosilicate glass is repeatedly applied by screen printing to form insulating paste layers **116a** to **116d** as shown in FIG. 3A. The insulating paste layers **116a** to **116d** are paste layers which are to be the insulator layers **16a** to **16d** that are insulator layers for outer layers, which are arranged at outer positions than the coils **L**.

Then, as shown in FIG. 3B, an insulating paste layer **116e** which has openings **h1**, **h2** is formed by photolithography. Specifically, a photosensitive insulating paste is applied by screen printing to form an insulating paste layer **116e** on the insulating paste layer **116d**. Further, the insulating paste layers are irradiated with ultraviolet light or the like via a photomask and are developed using an alkaline solution or the like. The insulating paste layer **116e** is a paste layer which is to be the insulator layer **16e**. Each of the openings **h1**, **h2** has a T-shape which is realized by joining two external conductor layers **35a**, **25a**. The openings **h1**, **h2** are joined together to have a cruciform shape.

Then, as shown in FIG. 3C, external conductor layers **25a**, **35a** are formed by photolithography. Specifically, a photo-

sensitive electrically-conductive paste whose metal main component is Ag is applied by screen printing to form an electrically-conductive paste layer on the insulating paste layer **116e**. Further, the electrically-conductive paste layer is irradiated with ultraviolet light or the like via a photomask and is developed using an alkaline solution or the like. Thereby, the external conductor layers **35a**, **25a** are formed in the openings **h1**, **h2**.

Then, as shown in FIG. 3B, an insulating paste layer **116f** which has openings **h3**, **h4** is formed by photolithography. Specifically, a photosensitive insulating paste is applied by screen printing to form an insulating paste layer **116f** on the insulating paste layer **116e**. Further, the insulating paste layer is irradiated with ultraviolet light or the like via a photomask and is developed using an alkaline solution or the like. The insulating paste layer **116f** is a paste layer which is to be the insulator layer **16f**. Each of the openings **h3**, **h4** has a T-shape which is realized by joining two external conductor layers **35b**, **25b**. The openings **h3**, **h4** are joined together to have a cruciform shape.

Then, as shown in FIG. 3C, external conductor layers **25b**, **35b** are formed by photolithography. Specifically, a photo-sensitive electrically-conductive paste whose metal main component is Ag is applied by screen printing to form an electrically-conductive paste layer on the insulating paste layer **116f**. Further, the electrically-conductive paste layer is irradiated with ultraviolet light or the like via a photomask and is developed using an alkaline solution or the like. Thereby, the external conductor layers **35b**, **25b** are formed in the openings **h3**, **h4**.

Then, as shown in FIG. 3D, an insulating paste layer **116g** which has openings **h5**, **h6** is formed by photolithography. Specifically, a photosensitive insulating paste is applied by screen printing to form an insulating paste layer **116g** on the insulating paste layer **116f**. Further, the insulating paste layer is irradiated with ultraviolet light or the like via a photomask and is developed using an alkaline solution or the like. The insulating paste layer **116g** is a paste layer which is to be the insulator layer **16g**. Each of the openings **h5**, **h6** has a T-shape which is realized by joining two external conductor layers **35c**, **25c**. The openings **h5**, **h6** are joined together to have a cruciform shape.

Then, as shown in FIG. 4A, the coil conductor layers **18a**, **20a** and external conductor layers **25c**, **35c** are simultaneously formed by photolithography. Specifically, a photosensitive electrically-conductive paste whose metal main component is Ag is applied by screen printing to form an electrically-conductive paste layer on the insulating paste layer **116g**. Further, the electrically-conductive paste layer is irradiated with ultraviolet light or the like via a photomask and is developed using an alkaline solution or the like. Thereby, the external conductor layers **35c**, **25c** are formed in the openings **h5**, **h6**, and the coil conductor layers **18a**, **20a** are formed on the insulating paste layer **116g**.

Then, as shown in FIG. 4B, an insulating paste layer **116h** which has openings **h7**, **h8** and via holes **H1**, **H5** is formed by photolithography. Specifically, a photosensitive insulating paste is applied by screen printing to form an insulating paste layer **116h** on the insulating paste layer **116g**. Further, the insulating paste layer is irradiated with ultraviolet light or the like via a photomask and is developed using an alkaline solution or the like. The insulating paste layer **116h** is a paste layer which is to be the insulator layer **16h**. Each of the openings **h7**, **h8** has a T-shape which is realized by joining two external conductor layers **35d**, **25d**. The openings **h7**, **h8** are joined together to have a cruciform shape.

Then, as shown in FIG. 4C, coil conductor layers **18b**, **20b**, external conductor layers **25d**, **35d**, and via hole conductors **v1**, **v5** are simultaneously formed by photolithography. Specifically, a photosensitive electrically-conductive paste whose metal main component is Ag is applied by screen printing to form an electrically-conductive paste layer on the insulating paste layer **116h**. Further, the electrically-conductive paste layer is irradiated with ultraviolet light or the like via a photomask and is developed using an alkaline solution or the like. Thereby, the external conductor layers **35d**, **25d** are formed in the openings **h5**, **h6**, the coil conductor layers **18b**, **20b** are formed on the insulating paste layer **116h**, and the via hole conductors **v1**, **v5** are formed in the via holes **H1**, **H5**.

Then, as shown in FIG. 4D, an insulating paste layer **116i** which has openings **h9**, **h10** and via holes **H2**, **H6** is formed by photolithography. Specifically, a photosensitive insulating paste is applied by screen printing to form an insulating paste layer **116i** on the insulating paste layer **116h**. Further, the insulating paste layer is irradiated with ultraviolet light or the like via a photomask and is developed using an alkaline solution or the like. The insulating paste layer **116i** is a paste layer which is to be the insulator layer **16i**. Each of the openings **h9**, **h10** has a T-shape which is realized by joining two external conductor layers **35e**, **25e**. The openings **h9**, **h10** are joined together to have a cruciform shape.

Then, as shown in FIG. 5A, coil conductor layers **18c**, **20c**, external conductor layers **25e**, **35e**, and via hole conductors **v2**, **v6** are simultaneously formed by photolithography. Specifically, a photosensitive electrically-conductive paste whose metal main component is Ag is applied by screen printing to form an electrically-conductive paste layer on the insulating paste layer **116i**. Further, the electrically-conductive paste layer is irradiated with ultraviolet light or the like via a photomask and is developed using an alkaline solution or the like. Thereby, the external conductor layers **35e**, **25e** are formed in the openings **h9**, **h10**, the coil conductor layers **18c**, **20c** are formed on the insulating paste layer **116i**, and the via hole conductors **v2**, **v6** are formed in the via holes **H2**, **H6**.

Then, as shown in FIG. 5B, an insulating paste layer **116j** which has openings **h11**, **h12** and via holes **H3**, **H7** is formed by photolithography. Specifically, a photosensitive insulating paste is applied by screen printing to form an insulating paste layer **116j** on the insulating paste layer **116i**. Further, the insulating paste layer is irradiated with ultraviolet light or the like via a photomask and is developed using an alkaline solution or the like. The insulating paste layer **116j** is a paste layer which is to be the insulator layer **16j**. Each of the openings **h11**, **h12** has a T-shape which is realized by joining two external conductor layers **35f**, **25f**. The openings **h11**, **h12** are joined together to have a cruciform shape.

Then, as shown in FIG. 5C, coil conductor layers **18d**, **20d**, external conductor layers **25f**, **35f**, and via hole conductors **v3**, **v7** are simultaneously formed by photolithography. Specifically, a photosensitive electrically-conductive paste whose metal main component is Ag is applied by screen printing to form an electrically-conductive paste layer on the insulating paste layer **116j**. Further, the electrically-conductive paste layer is irradiated with ultraviolet light or the like via a photomask and is developed using an alkaline solution or the like. Thereby, the external conductor layers **35f**, **25f** are formed in the openings **h11**, **h12**, the coil conductor layers **18d**, **20d** are formed on the insulating paste layer **116j**, and the via hole conductors **v3**, **v7** are formed in the via holes **H3**, **H7**.

Then, as shown in FIG. 5D, an insulating paste layer **116k** which has openings **h13**, **h14** and via holes **H4**, **H8** is formed by photolithography. Specifically, a photosensitive insulating paste is applied by screen printing to form an insulating paste layer **116k** on the insulating paste layer **116j**. Further, the insulating paste layer is irradiated with ultraviolet light or the like via a photomask and is developed using an alkaline solution or the like. The insulating paste layer **116k** is a paste layer which is to be the insulator layer **16k**. Each 10 of the openings **h13**, **h14** has a T-shape which is realized by joining two external conductor layers **35g**, **25g**. The openings **h13**, **h14** are joined together to have a cruciform shape.

Then, as shown in FIG. 6A, coil conductor layers **18e**, **20e**, external conductor layers **25g**, **35g**, and via hole conductors **v4**, **v8** are simultaneously formed by photolithography. Specifically, a photosensitive electrically-conductive paste whose metal main component is Ag is applied by screen printing to form an electrically-conductive paste layer on the insulating paste layer **116k**. Further, the electrically-conductive paste layer is irradiated with ultraviolet light or the like via a photomask and is developed using an alkaline solution or the like. Thereby, the external conductor layers **35g**, **25g** are formed in the openings **h13**, **h14**, the coil conductor layers **18e**, **20e** are formed on the insulating paste layer **116k**, and the via hole conductors **v4**, **v8** are formed in the via holes **H4**, **H8**.

Then, as shown in FIG. 6B, an insulating paste layer **116l** which has openings **h15**, **h16** is formed by photolithography. Specifically, a photosensitive insulating paste is applied by screen printing to form an insulating paste layer **116l** on the insulating paste layer **116k**. Further, the insulating paste layer is irradiated with ultraviolet light or the like via a photomask and is developed using an alkaline solution or the like. The insulating paste layer **116l** is a paste layer which is to be the insulator layer **16l**. Each of the openings **h15**, **h16** has a T-shape which is realized by joining two external conductor layers **35h**, **25h**. The openings **h15**, **h16** are joined together to have a cruciform shape.

Then, as shown in FIG. 6C, external conductor layers **25h**, **35h** are formed by photolithography. Specifically, a photosensitive electrically-conductive paste whose metal main component is Ag is applied by screen printing to form an electrically-conductive paste layer on the insulating paste layer **116l**. Further, the electrically-conductive paste layer is irradiated with ultraviolet light or the like via a photomask and is developed using an alkaline solution or the like. Thereby, the external conductor layers **35h**, **25h** are formed in the openings **h15**, **h16**.

Then, as shown in FIG. 6B, an insulating paste layer **116m** which has openings **h17**, **h18** is formed by photolithography. Specifically, a photosensitive insulating paste is applied by screen printing to form an insulating paste layer **116m** on the insulating paste layer **116l**. Further, the insulating paste layer is irradiated with ultraviolet light or the like via a photomask and is developed using an alkaline solution or the like. The insulating paste layer **116m** is a paste layer which is to be the insulator layer **16m**. Each of the openings **h17**, **h18** has a T-shape which is realized by joining two external conductor layers **35i**, **25i**. The openings **h17**, **h18** are joined together to have a cruciform shape.

Then, as shown in FIG. 6C, external conductor layers **25i**, **35i** are formed by photolithography. Specifically, a photosensitive electrically-conductive paste whose metal main component is Ag is applied by screen printing to form an electrically-conductive paste layer on the insulating paste layer **116m**. Further, the electrically-conductive paste layer is irradiated with ultraviolet light or the like via a photomask

and is developed using an alkaline solution or the like. Thereby, the external conductor layers 35i, 25i are formed in the openings h17, h18.

Then, as shown in FIG. 6D, an insulating paste is repeatedly applied by screen printing to form insulating paste layers 116n to 116q. The insulating paste layers 116n to 116q are paste layers which are to be the insulator layers 16n to 16q that are insulator layers for outer layers, which are arranged at outer positions from the coils L. Throughout the above-described process, a mother multilayer body 112 is obtained.

Then, the mother multilayer body 112 is cut into a plurality of unsintered multilayer bodies 12 by dicing or the like. In the step of cutting the mother multilayer body 112, the external electrodes 14a, 14b are exposed from the multilayer body 12 at cut surfaces which are formed by cutting.

Then, the unsintered multilayer bodies 12 are sintered under predetermined conditions, whereby the multilayer bodies 12 are obtained. Further, the multilayer bodies 12 are subjected to barrel processing.

Lastly, a Ni plating layer which has a thickness of 2 μm to 7 μm and a Sn plating layer which has a thickness of 2 μm to 7 μm are formed over portions in which the external electrodes 14a, 14b are exposed from the multilayer body 12. Throughout the above-described process, the electronic component 10 is completed.

Effects

According to the electronic component 10 which has the above-described configuration, the positional relationship between the external electrodes 14a, 14b and the coils L1, L2 is unlikely to deviate from a predetermined positional relationship. More specifically, in the case of an electronic component in which an external electrode is formed in a surface of a multilayer body after formation of the multilayer body that includes a coil, the positional relationship between the external electrode and the coil is likely to deviate from a predetermined positional relationship due to, for example, a variation in the cut position of the multilayer body or a variation in formation of the external electrode.

On the other hand, in the case of the electronic component 10, the external conductor layers 25c to 25g and 35c to 35g, which are provided on the same insulator layers 16g to 16k on which the coil conductor layers 18a to 18e and 20a to 20e are provided, are formed by photolithography simultaneously with formation of the coil conductor layers 18a to 18e and 20a to 20e. Therefore, the position accuracy of the coil conductor layers 18a to 18e and 20a to 20e and the external conductor layers 25c to 25g and 35c to 35g depends on the accuracy of photolithography. Thus, in the case of the electronic component 10, the positional relationship between the external electrodes 14a, 14b and the coils L1, L2 is unlikely to deviate from a predetermined positional relationship as compared with an electronic component in which an external electrode is formed in a surface of a multilayer body after formation of the multilayer body that includes a coil.

Further, the electronic component 10 can readily have a structure which can be configured to have arbitrary electric characteristics. FIG. 7 is an equivalent circuit diagram of the electronic component 10. FIG. 8 is a graph showing the relationship between the frequency and the attenuation of the output signal relative to the input signal in the electronic component 10. The horizontal axis represents the frequency, and the vertical axis represents the attenuation.

In the electronic component 10, the coils L1, L2 are connected in series between the external electrodes 14a, 14b

as shown in FIG. 7. The external electrodes 14a, 14b face on the coils L1, L2, respectively, so that capacitors C1, C2 are respectively formed between the external electrodes 14a, 14b and the coils L1, L2. With this configuration, the electronic component 10 forms a noise filter which has two resonant frequencies shown in FIG. 8.

Here, in the electronic component 10, the external electrode 14a and the external electrode 14b have different shapes. Therefore, the shape of each of the external electrodes 14a, 14b can be independently designed, and the capacitors C1, C2 can be formed so as to have arbitrary capacitance values. As a result, the two resonant frequencies shown in FIG. 8 can be changed. In view of the foregoing, the electronic component 10 can have a structure which can be configured to have arbitrary electric characteristics.

First Variation

Next, an electronic component 10a according to the first variation is described with reference to the drawings. FIG. 9 is an exploded perspective view of the electronic component 10a according to the first variation.

The difference between the electronic component 10a and the electronic component 10 resides in the shape of the external electrode 14a. Specifically, in the electronic component 10, the external electrode 14a and the external electrode 14b are equal in terms of the shape of a portion of the external electrode 14a which is exposed from the multilayer body 12 and the shape of a portion of the external electrode 14b which is exposed from the multilayer body 12. However, they have different thicknesses in these portions so that they have different shapes.

On the other hand, in the electronic component 10a, the shape of a portion of the external electrode 14a which is exposed from the multilayer body 12 and the shape of a portion of the external electrode 14b which is exposed from the multilayer body 12 are different so that the external electrodes 14a, 14b have different shapes. The external electrode 14a extends over the lateral surfaces S1, S3, S2 and has an inverted C shape when viewed in plan from the y-axis direction. On the other hand, the external electrode 14b extends over the lateral surfaces S2, S4 and has an L shape. In the present embodiment, the thickness of the external electrode 14a and the thickness of the external electrode 14b are equal. Note that, however, the thickness of the external electrode 14a and the thickness of the external electrode 14b may be different.

In the electronic component 10a which has the above-described configuration, the external electrode 14a is provided in the lateral surface S1. The lateral surface S1 is a surface which is on the upper side when the electronic component 10a is mounted. Therefore, a portion of the external electrode 14a which is provided in the lateral surface S1 can be used as a direction indicator mark. Thus, in the electronic component 10a, it is not necessary to form an additional direction indicator mark.

In the electronic component 10a, the area of a portion of the external electrode 14a which faces on the coil L1 and the area of a portion of the external electrode 14b which faces on the coil L2 can be arbitrarily set. Due to this feature, the electronic component 10a can have a structure which can be configured to have arbitrary electric characteristics.

Second Variation

Next, an electronic component 10b according to the second variation is described with reference to the drawings. FIG. 10 is an exploded perspective view of the electronic component 10b according to the second variation.

The difference between the electronic component 10b and the electronic component 10 resides in the number of coils.

11

Specifically, the electronic component **10** includes the coils **L1**, **L2**. On the other hand, the electronic component **10a** only includes a coil **L3**. Thus, the number of coils is not limited to two.

Third Variation

Next, an electronic component **10c** according to the third variation is described with reference to the drawings. FIG. 11 is a perspective view of the exterior of the electronic component **10c** according to the third variation.

The difference between the electronic component **10c** and the electronic component **10** resides in the shape of the external electrode **14a**. More specifically, in the electronic component **10**, the external electrode **14a** has a certain thickness as shown in FIG. 1. On the other hand, in the electronic component **10c**, the thickness of the external electrode **14a** decreases toward the positive direction side of the y-axis direction. This varying thickness of the external electrode **14a** enables the capacitor **C1** to have a varying capacitance.

An electronic component according to the present disclosure is not limited to the electronic components **10**, **10a** to **10c** of the above-described embodiments but can be modified within the scope of the spirit of the disclosure.

In the electronic component **10**, the coil conductor layers **18**, **20** are to be formed by photolithography but may be formed by printing.

What is claimed is:

1. An electronic component comprising:
a multilayer body having a shape of a rectangular parallelepiped, and including a plurality of stacked insulator layers;
a first coil including two or more first coil conductor layers respectively provided on two or more consecutive insulator layers of the plurality of stacked insulator layers; and
first and second external electrodes embedded in a lateral surface of the multilayer body which is formed by a series of continuous perimeter edges of the plurality of stacked insulator layers, each of the first and second external electrodes including a plurality of stacked external conductor layers embedded in the lateral surface of the multilayer body, the plurality of stacked

external conductor layers of each of the first and second external electrodes being provided on the plurality of stacked insulator layers, the first and second external electrodes being electrically connected to the first coil, wherein one of the stacked external conductor layers of

each of the first and second external electrodes is provided on each of the two or more consecutive insulator layers, and

the stacked external conductor layers on each of the two or more consecutive insulator layers have different shapes from each other.

2. The electronic component according to claim 1, further comprising a second coil including at least one second coil conductor layer provided on at least one of the plurality of stacked insulator layers, wherein the stacked external conductor layers and the second coil conductor are photolithographed or printed on the same insulator layer.

3. The electronic component according to claim 1, wherein a thickness of the first external electrode is different from a thickness of the second external electrode.

4. The electronic component according to claim 1, wherein a shape of a portion of the first external electrode which is exposed from the multilayer body is different from a shape of a portion of the second external electrode which is exposed from the multilayer body.

5. The electronic component according to claim 1, wherein

the first external electrode extends over three lateral surfaces, and

the second external electrode extends over two lateral surfaces.

6. The electronic component according to claim 5, wherein

the first external electrode extends over the three lateral surfaces in plan view in a stacking direction of the plurality of stacked insulator layers, and

the second external electrode extends over only the two lateral surfaces in plan view in the stacking direction, the first coil having a helical shape around an axis parallel to the stacking direction.
